UNITED STATES PATENT OFFICE

CHESTER W. CRUMRINE, OF ROCHESTER, NEW YORK, ASSIGNOR TO ELECTROMATIC TYPEWRITERS, INC., OF ROCHESTER, NEW YORK, A CORPORATION OF NEW YORK

PAPER ROLLER MECHANISM

Application filed December 9, 1926. Serial No. 153,588.

This invention relates to the rollers used to press the paper against the platen in a typewriter or similar machine.

The object of the invention is to provide a mechanism by which each of two parallel paper-rollers may be pressed against the paper with a force which is equal as to the two ends of the roller, regardless of variations in the thickness of the paper, while at the same time the axes of the rollers are held substantially parallel with each other, and as nearly as possible parallel with the axis of the platen. To this end the invention consists in a construction, hereinafter more particularly described, by which the rollers are supported with freedom in every respect necessary for their relative compensatory movements, and in which the resilient pressure is applied to the rollers through mechanism by which it is automatically equalized as between the two rollers and the two ends of each roller.

In the accompanying drawings Fig. 1 is a plan-view of the mechanism embodying the present invention, with certain details shown in section. Fig. 2 is an end-view of the mechanism, together with the platen of a typewriter; and Fig. 3 is a detail view showing the loose pivotal connection between the front paper-roller and one of the end-levers.

The invention is illustrated as embodied in a mechanism comprising two parallel paper-rollers, which are pressed upwardly against the lower part of the platen in a well known manner. The rear roller 5 has a continuous surface, of rubber or other suitable material, while the front roller comprises a rod 6, upon which are three detached contact portions 7 of rubber. These rollers cooperate with the platen 8 of the typewriter, as shown in Fig. 2.

The two rollers are supported, at their ends, by two end-levers 9. Each end of the rear roller 5 has a pivotal connection with the rear end of the respective end-lever, by means of a trunnion 10 which is fitted so loosely in the lever that it may not only rotate, but also have the slight angular movements necessary for compensation. Each lever 9 is perforated at an intermediate point 50 of its length, and a rod 11 is pivoted at its

ends in these perforations, being loosely fitted as in the case of the trunnions 10, so as to permit slight angular as well as relative rotative movements of the end-levers.

In the arrangement so far described, it will be evident, if upward pressure be applied to the middle of the rod 11 this pressure will be transmitted to the middle points of the end-levers, while the levers will press the rollers upwardly against the platen or the paper, and, owing to the central application of such pressure on the rod, the force applied to the levers will be equalized, thus equalizing the pressure as between the two ends of each paper-roller. At the same time, owing to the freedom for relative rotation and angular movements of the rollers and the levers, each roller is sufficiently free to accommodate itself to any slight differences in the thickness of the paper or to compensate for any inaccuracies in the form of the platen or of either roller.

As a convenient means for applying the resilient pressure to the middle of the rod 11, a rock-shaft 12 is journalled, at its ends, in plates 13 which may be the usual end-plates of the carriage of the typewriter. An arm 14 is adjustably fixed to the middle of the rock-shaft, and the end of this arm is perforated to receive the rod 11, the connection at this point preferably being loose enough to permit relative angular movements of the arm and the rod. At each end of the rock-shaft 12 a coil spring 15, attached to an adjustable collar 16, acts to turn the rock-shaft 12 in a direction to swing the arm upwardly and thus transmit the desired pressure and movement to the rod 11.

The cooperative action of the rollers and the platen is such as to tend to maintain them in position with their axes parallel, but to secure such parallelism more positively, without interfering with the compensating movements of the rollers, means are preferably provided in the form of links 17, of which the rear ends have loose pivotal connection with the rod 11. The front ends of these links are loosely pivoted upon the rock-shaft 12, between collars 18.

Owing to the loose connections of the sev-

eral parts, as above described, it is desirable to provide means for preventing endwise movement of the rollers and their supporting mechanism. For this purpose a plate 19 is shown, fixed at its lower end to a part 20 of the carriage, this plate having a vertical slot which engages and guides one of the end-levers 9.

5 The invention claimed is:

- 10 Paper-roller mechanism, for a typewriter or the like, comprising two parallel rollers, two end-levers each having loose pivotal connections with the corresponding ends of said rollers, a rod loosely connected, at its ends, 15 with intermediate points of the respective end-levers, a rock-shaft parallel with said rollers and rod, an arm fixed to the rock-shaft and having a loose pivotal engagement with the middle of said rod, two links, each 20 loosely pivoted, at its ends, to the rod and the rock-shaft, respectively, and a spring for rotating the rock-shaft in the direction to press the rollers against the paper.
